(74) Attorney, Agent, or Firm — Fross, Zelnick, Lehrman & Zissu PC; Charles T. J. Weigell, Esq.

(57) **CLAIM**

The ornamental design for a display screen with graphical user interface, as shown and described.

DESCRIPTION

The sole FIGURE is a view of a display screen with graphical user interface showing our new design.

The outmost broken line rectangle illustrates the display screen. The remaining broken lines, including all text shown, illustrate portions of the graphical user interface. None of the broken lines form part of the claimed design.

1 Claim, 1 Drawing Sheet(56)
